M. Hainque,
Ratchet Drill,

N° 79,115.

Patented June 23, 1868.

Inventor:

Martial Hainque

United States Patent Office.

MARTIAL HAINQUE, OF SAN FRANCISCO, CALIFORNIA, ASSIGNOR TO HIMSELF AND JOHN LOWTH, OF SAME PLACE.

Letters Patent No. 79,115, dated June 23, 1868.

IMPROVED DRILL-STOCK.

The Schedule referred to in these Letters Patent and making part of the same.

TO ALL WHOM IT MAY CONCERN:

Be it known that I, MARTIAL HAINQUE, of the city and county of San Francisco, and State of California, have invented a new and improved Implement or Tool for Drilling Metals by Hand; and I do hereby declare that the following is a full, clear, and exact description of the same, reference being had to the accompanying drawings, making a part of this specification, in which—

Figure 1 is a vertical section,

Figure 2 is a sectional plan,

Figure 3 an elevation, and

Figures 4, 5, 6, 7, and 8, detached details of the parts.

To enable others skilled in the art to make and use my invention, I will proceed to describe its construction and operation, as follows:

I make of suitable material my drill-stock A, figs. 1, 2, and 3, having at bottom the usual socket for drill, and immediately above, a shoulder, *a*, upon which the sleeve-piece B rests; thence upwards from this shoulder, for a distance corresponding with the width of the sleeve B, it is turned, and finished to fit this sleeve; thence above, terminating in the usual feed-screw.

The sleeve-piece B may be made of cast malleable iron or other suitable material, and is formed to fit and revolve around the drill-stock A, having projecting lugs, *b*, to form a fulcrum for the handle or lever, and through which the fulcrum-pin passes. This sleeve is slotted between the lugs, to admit the introduction of the gib C, and may be made with a cavity for an additional back gib, C', fig. 8, or plain, as shown in fig. 4, accordingly as in practice it may be found better. The gib C C' are made of hardened steel, and are formed to fit around the drill-stock, and make an easy fit in the sleeve-piece B.

The handle or lever D may be made of cast malleable iron or other suitable material, and has its fulcrum-end formed eccentrically or cam-shaped, and bears directly against the gib C. Upon the side of this handle is attached a stout spring, *d*, which, bearing against the sleeve-piece B, tends to set back the lever or handle, and keeps the cam-bearing against the gib, thus avoiding "back-lash" or looseness. This handle is connected with the sleeve-piece B by the fulcrum-pin, as shown in fig. 1.

Immediately above the sleeve B, and to keep the same in place, is provided a check-nut, E, which screws down to a shoulder on the feed-screw. This may also be made of cast malleable iron.

The compensating-sleeve F is similar to those ordinarily used for like purposes, and needs no description here.

I may here remark that the gib-pieces C C' may be either made plain, as shown in fig. 6, or with corrugated or V-shaped grooves, as shown in fig. 7, the drill-stock against which they press being at that point provided with corresponding rings, which shall fit in these grooves, to increase the frictional surface.

The operation and principle of the tool is as follows:

The handle or lever D, having an eccentrically or cam-shaped end, being directly in contact with the gib C, will, when never so slightly moved in an inward direction upon its fulcrum, bind this gib against the drill-stock A, when, by reason of the created friction, it will cease to revolve around the drill-stock, but will, if the lever be continued in its revolution about the axis of the drill, carry the drill-stock with it, and thus perform the drilling until the stroke is finished, when, by a slight movement of the handle in an opposite direction, the pressure against the gib is released, and the friction ceasing, the handle, sleeve, and gib are easily set back, swinging loosely around the drill-stock as far as is convenient to obtain another purchase, when the operation is repeated.

It will easily be perceived that the principle here involved is also applicable to other machines, for instance, the anchor-winch of a ship, or any other machine where the ordinary pawl and ratchet finds use, the which my machine is intended to replace.

What I claim as my invention, and desire to secure by Letters Patent, is—

The combination of the drill-stock A with the lever D, the plain or corrugated gib C, and the sleeve B, the said parts being constructed and arranged substantially as described.

MARTIAL HAINQUE.
